UNITED STATES PATENT OFFICE.

SAMUEL J. BENS, OF BERKELEY, AND ALBERT B. HUBBARD, OF OAKLAND,
CALIFORNIA.

TOILET-PAPER HOLDER.

1,069,757.

Specification of Letters Patent. Patented Aug. 12, 1913.

Application filed April 1, 1913. Serial No. 758,211.

To all whom it may concern:

Be it known that we, SAMUEL J. BENS and ALBERT B. HUBBARD, citizens of the United States, residing at Berkeley and 5 Oakland, California, respectively, have invented certain new and useful Improvements in Toilet-Paper Holders, of which the following is a specification.

Our invention is designed to provide a 10 simple inexpensive and effective holder for a roll of toilet paper, and it consists in the features and combination and arrangement of parts hereinafter described and particularly pointed out in the claims.

15 In the accompanying drawings Figure 1 is a perspective view of our invention, Fig. 2 is a plan view, and Fig. 3 is a side elevation.

In these drawings 1 is the main frame 20 consisting in its preferred form of a back or base piece 1 and forwardly extending arms 2. While these may be variously made and of different kinds of material, we prefer to use simply a piece of flat strap metal bent 25 at right angles to form the base and the projecting arms. This frame supports the roller carrying frame composed of wire, which frame is of U shape, one arm 3 passing through openings in the arms 2 and 30 along the front face of the main portion, this arm being adapted to rotate in said openings while the other arm 5 carries the roller 6 on which the roll of paper may be placed by thrusting it over the end of the roller. 35 By reason of the U shaped form of the frame with the roller supported on its free end the roll of paper may be placed in the roller by simply lifting the U shaped frame and then pushing the paper roll onto the 40 same from one end. The free end of the U shaped frame is supported by the arms 2. These arms thus perform a double function, *i. e.*, that of supporting the U shaped frame with the roll of paper and further that of 45 serving as guards at the sides of the paper roll when in place to hold said roll in proper position on the roller 6.

Preferably we provide recesses in the upper edges of the arms 2 to receive the free 50 arm of the U-shaped frame, and we prefer to form the ends of the arms 2 with their upper edges slightly bent outwardly, as shown at 7.

The roller 6 is held on the arm of the U-shaped pivoted frame by any suitable means, 55 such as the collar or rib 8.

The supporting frame may be constructed differently from that shown, but in either case at least one forwardly extending arm will be employed to act as a support for the 60 roller carrying frame and as a guard for the roller.

We claim:—

1. A holder for a toilet paper roll consisting of a frame having a base portion with 65 a forwardly projecting arm, a U-shaped frame having one arm rotatively mounted in the frame, a roller mounted on the free arm of said U-shaped frame, said U-shaped frame being supported at its free end by 70 said arm, substantially as described.

2. A holder for a toilet paper roll comprising a frame consisting of a base portion with forwardly extending arms, a U-shaped frame having one arm rotatively mounted in 75 the forwardly extending arms, a roller on the free arm of said U-shaped frame, said free arm resting on the forwardly projecting arms of the main frame, substantially as described. 80

3. A holder for a roll of toilet paper consisting of a base and forwardly extending arms bent up from a flat strip of metal, a wire frame of U-shape having one arm rotatively mounted in the forwardly extending arms of the main frame, the free arm of 85 said U-shaped frame being supported by the arms of the main frame and a roller on said free arm, substantially as described.

4. A holder for a roll of toilet paper consisting of a main frame having a base and forwardly extending arms and a U-shaped frame having an arm rotatively mounted in the main frame and the arms of said main frame having notches to receive the free arm 95 of said U-shaped frame, and a roller on said free arm, substantially as described. 90

In testimony whereof, we affix our signatures in presence of two witnesses.

SAMUEL J. BENS.
ALBERT B. HUBBARD.
